US00D610288S

(12) **United States Design Patent**
Boissevain

(10) **Patent No.:** **US D610,288 S**
(45) **Date of Patent:** **** Feb. 16, 2010**

(54) **LUMINAIRE**(75) Inventor: **Chris Boissevain**, Wimberley, TX (US)(73) Assignee: **Koninklijke Philips Electronics N.V.**,
Eindhoven (NL)(**) Term: **14 Years**(21) Appl. No.: **29/328,736**(22) Filed: **Dec. 1, 2008**(51) **LOC (9) Cl. 26-05**(52) **U.S. Cl. D26/71; D26/92**(58) **Field of Classification Search** D26/67-72,
D26/85, 92; 362/145, 152, 183, 294, 373,
362/414, 431, 545

Primary Examiner—Clare E Heflin(74) *Attorney, Agent, or Firm*—John F. Salazar; Middleton Reutlinger(57) **CLAIM**

The ornamental design for a luminaire, as shown and described.

DESCRIPTION

FIG. 1 is a top perspective view of the luminaire of the present invention;

FIG. 2 is a top view of the luminaire of FIG. 1;

FIG. 3 is a bottom view of the luminaire of FIG. 1;

FIG. 4 is a left side elevation view of the luminaire of FIG. 1;

FIG. 5 is a right side elevation view of the luminaire of FIG. 1;

FIG. 6 is a front view of the luminaire of FIG. 1; and,

FIG. 7 is a rear view of the luminaire of FIG. 1.

The broken lines showing environmental structure are for illustrative purposes only and form no part of the claimed design.

1 Claim, 7 Drawing Sheets# US D610,288 S
